RAZOR BLADE SHARPENER

Filed May 31, 1930

UNITED STATES PATENT OFFICE

2,008,211

RAZOR BLADE SHARPENER

John Holtzman, New York, N. Y.

Application May 31, 1930, Serial No. 458,150

9 Claims. (Cl. 51—153)

This invention relates to devices for holding and stropping safety razor blades of all types, and is intended to be an improvement upon the structure disclosed in Patent No. 1,399,241, dated December 6th, 1921, for Device for sharpening blades for safety razors, granted to Wilhelm Barsch.

In the device shown in the patent referred to, a sharpening body is provided, surfaced on one face with a strop, and on the other face, with a hone. It is customary to first hone the blade, when necessary, and then to strop it. However, previous devices such as that shown in Patent No. 1,399,241 necessitate the removal of the blade from the machine after the blade has been honed and the rearrangement thereof on the other side of the machine so that the edge of the blade may be drawn across the stropping surface on the opposite face of the sharpening body.

My invention contemplates the provision of means whereby the blade need not be disturbed during either the stropping or the honing operations or in the change from one operation to the other. My invention further contemplates the provision of means for allowing rapid and efficient change from the honing to the stropping operation without the necessity for handling the blade with the consequent danger of injury to the user. My invention further contemplates the provision of simple, efficient and inexpensive means for maintaining the blade in contact with the sharpening surface during either sharpening operation, and further contemplates the provision of a device simplified in construction whereby a blade may be both honed and stropped in a comparatively short time.

The various objects of my invention will be clear from the description which follows, and from the drawing, in which

Fig. 1 is a top plan view of my improved device.

Fig. 2 is a vertical section of the same, taken on the line 2—2 of Fig. 1.

Fig. 3 is a similar section, taken on the line 3—3 of Fig. 1 and showing the reciprocatory blade supporting means.

Fig. 4 is a similar section, taken on the line 4—4 of Fig. 1, and

Fig. 5 is a transverse section of the sharpening member and of the means for rotatably supporting said member for quick change from the stropping to the honing operation.

In that practical embodiment of my invention which I have illustrated by way of example, a stationary frame as 10 is provided, on which

the various movable parts are mounted. The side walls of the frame are each formed from a channel-shaped member 11 provided with a pair of horizontal flanges as 12 and 13 and having a web as 14 joining the flanges. A similar channel as 15 opposed to the channel 11 is provided at the other side of the frame, said channels being joined by the end members 16 and 17 secured to the side channels as by means of suitable screws or rivets 18. The end members 16 and 17 further support the bearing plate 19, which plate terminates at its ends inwardly of the ends of the device and which is provided at its side edges with a pair of rails as 20 and 21 extending forwardly toward the end member 16 and secured thereto. The rails 20 and 21 are also extended rearwardly into engagement with the end member 17 and there secured in place.

At the forward edge 22 of the plate 19, a recess as 23 is made and in said recess is pivotally mounted a suitable reversing roller as 24 for completing the reversal of the blade in a manner which is well known in the art and which need not be further described.

The plate 19 is further provided with a substantially central aperture 25 conforming to the outline of the sharpening member 26 and in which said member is set to project substantially the same distance above the top of the plate 19 and below the bottom thereof. The sharpening member 26 is further provided with a pair of similar recesses 27 and 28. Each of said recesses is adapted to be engaged in turn by the slide catch 29 which is slidably supported on the upper surface of the plate 19 as by means of the loop 30, preferably struck up from and integral with the remainder of the plate 19. The slide catch 29 may terminate in a handle loop as 31 to provide for easy handling by the user. For preventing the complete withdrawal of the slide catch from the loop 28 and to further prevent loss of said catch, a suitable stop as 32 may be struck up from the plate 19 so as to prevent said catch from being completely detached from the plate.

The sharpening member 26 is preferably provided with end holes as 33 arranged coaxially of said member and coaxially with each other. A pin as 34 terminating in a suitable conical bearing point 35 is inserted into each of the holes and is normally pressed outwardly of the member 26 as by means of a compression spring 36. For supporting the pins 34, part of each of the rails 20 and 21 and part of the material removed from the aperture 25 may be bent obliquely to the remainder of the rail to form a bearing plate as 55

37 which is provided with a suitable aperture for the reception of the conical end 35 of the pins 34. It will be understood that the springs 36 press the bearing pins 34 outwardly so as to maintain 5 said pins in the apertures of the bearing projections 37, and that when the sharpening member 26 is freed of the slide catch 31, said member may be freely rotated in the aperture 25 about the pins 34 into the position desirable for bringing either the honing surface 38 or the stropping surface 39 uppermost into sharpening position.

10 I have shown the double edge blade 40 suitably supported in the blade holder 41 in a manner which is well known but it will be understood 15 that by the provision of a suitable holder, a single edge blade may also be sharpened in my improved device. The blade holder 41 may be of any suitable type such as that wherein two halves 20 are hinged together at one end and secureable in closed position about the blade near their other ends. As shown particularly in Figs. 1 and 4, the blade holder terminates in suitable pins as 42 secured as by riveting or in any other suitable manner to the friction blocks 43. Said blocks are 25 designed to contact with the underface 44 of the channels 11 and 12 for the purpose of rotating the blade holder and the blade carried thereby when the direction of reciprocation of the blade holder is reversed so that both edges of a double 30 edge blade may be sharpened. It will be seen, therefore, that both sides of the blade at both cutting edges are sharpened in succession by the 35 partial rotation of the blade holder and by the completion of the reversal of the blade holder by the roller 24 when the blade support is carried forwardly and backwardly to the limits of its stroke in either direction.

40 For reciprocating the blade holder and the blade carried thereby, I provide a manually reciprocable carriage as 45 which includes the handle portion 46 by means of which the entire carriage together with the blade holder may be pushed forwardly and rearwardly. The handle 46 is secured at the side of the device to a pair 45 of plates 47 which are arranged to reciprocate between the flanges of the channels 14 and 15. At its lower edge, each of the plates 47 is provided with a substantially horizontal flange as 48 to which is secured the sheet spring 49. Said 50 spring engages the uppermost surface of the lower channel flange and serves to urge the entire carriage, including the plate 47 and the blade holder 41, upwardly to bring the upper edge of the friction cam 43 and the horizontal part 58 of the upper edge of the plate 47 into frictional contact 55 with the under face of the upper flange of the side channel. It will be noted that the remainder 51 of the upper edge of the plate 47 is inclined downwardly in a forward direction for the purpose soon to be described. The inner face of 60 the plate 47 engages the outer face of the rail 20 and is guided thereby for straight line movement as the carriage is reciprocated.

65 It will be understood that a pair of plates 47 are provided as well as a pair of springs 49, one for each of the channels 11 and 15 so that the above description of one of the plates will suffice for both. It will further be seen that as the carriage is pushed forwardly toward the end piece 16, the friction cam 43 is rotated in a clockwise direction as viewed in Fig. 2 to bring the rear edge of the blade 40 into contact with the sharpening surface of the member 26. As the carriage 70 45 approaches the limit of its forward movement, and the rear edge of the blade leaves the member

26, said rear edge engages the roller 24 and on further movement, said rear edge leaves the roller. When this occurs, the spring 49 is free to move 5 the plate 47 upwardly since the friction cam 43 under pressure of the spring 49 is rotated to bring its flat edge 55 into contact with the under face of the upper channel flange. Not only, therefore, is the inclined edge 51 of the plate 47 and the entire carriage as well moved upwardly by the spring 49 but the blade holder is simultaneously 10 rotated by the same spring 49, ready for the reversal action of the roller 24 when the direction of movement of the carriage 45 is reversed. On such reversal of the carriage or rearward movement thereof, the opposite face of the blade is 15 engaged by the roller and the blade holder 41 further rotated in a clockwise direction until the lower curved cam surface 59 of the friction cam is brought into engagement with the under face 20 of the upper channel flange whereupon the plate 47 is depressed against the action of the spring 49 and the inclined edge 51 thereof withdrawn from its engagement with the channel flange and the forward edge of the blade 40 brought into 25 engagement with the sharpening surface.

30 After the blade edges have been sufficiently honed by the reciprocation thereof across the hone 38, the blade need not be disturbed but the sharpening member 26 may be quickly and easily reversed. Such reversal of the sharpening member to bring the stropping surface 39 uppermost is effected by the withdrawal of the slide catch 31 from the recess 28 and the rotation of the member 26 about the pins 34 through a half revolution. Such rotation brings the recess 27 35 into alignment with the slide catch whereafter said slide catch may be inserted into the recess 27 and the member 26 thereby retained in stropping relation to the blade.

40 It will be noted that the blade holder 41 is inserted into the slot 56 of the plates 47 and may be readily removed therefrom together with the blade when the carriage reaches its extreme forward position normally, the projecting ends 57 of the spring wire 58 are interposed in the path 45 of the carriage so that the edge 59 of said carriage engages the ends 57 and limits the forward movement thereof. When it is desired to remove the blade, however, the loop 60 of the spring wire 58 is raised, thereby swinging said wire about its 50 pivot 61 and depressing the projections 57 so that said projections are aligned with the slots 62 of the plates 47 and further forward movement of the carriage is permitted. Said further forward movement carries the friction cams 43 beyond 55 the terminal ends 63 of the flanges of the channels 11 and 15 whereby the blade-holder is freed of the channels and may be raised out of the slots 56 and the sharpened blade removed therefrom or another blade inserted thereinto.

60 It will be seen that the devices herein shown and described are simple, capable of economical manufacture and designed to meet the severe requirements of practical use.

65 It will further be understood that while I have shown and described a specific embodiment of my invention, I do not wish to be understood as limiting myself thereto but intend to claim my invention as broadly as may be permitted by the state of the prior art and the terms of the appended claims.

70 I claim:

75 1. In a razor stropping device, the combination of a frame, a pair of channels formed in said frame, a carriage slidably mounted in said chan-

- nels for manual reciprocation, a blade holder rotatably mounted in said carriage, spring means interposed between said carriage and said channels for imparting vertical movement to said carriage at the end of its stroke, whereby said blade holder is rotated, a sharpening element mounted diagonally of the device on said frame, means for supporting said element for rotation in the frame relative thereto, and means cooperating with the blade to dispose all four edgesides of the blade to said sharpening element individually and successively. 5
2. A device for sharpening razor blades having two cutting edges, comprising in combination, a frame having channels therein, a carriage slidably arranged in said frame, a sharpening element arranged obliquely to the path of the movement of the carriage, means in said frame for supporting the sharpening element to permit rotation thereof relative to said frame, said sharpening element having a recess therein, a blade holder rotatably mounted in said carriage, discs fixed to the blade holder, a spring fixed to said carriage, said discs being pressed against the channels of said frame for reversing of the blade and for pressing the same against the sharpening element, said element having a honing side and a stropping side, slidable means mounted on said frame cooperating with the recess in said sharpening element for locking said element against free rotation thereof and for disposing the honing or stropping side of said element to the razor blade when the same is actuated by the manual reciprocation of said carriage longitudinally of said frame. 10
3. In a razor stropping device, the combination of a frame, a pair of channels formed in said frame, a carriage slidably mounted in said channels for manual reciprocation, a blade holder rotatably mounted in said carriage, spring means interposed between said carriage and said channels for imparting vertical movement to said carriage, whereby said blade holder is rotated, a reversible sharpening element mounted diagonally of the device on said frame, means for supporting said element for rotation in the frame relatively thereto, comprising pins at the ends of the element and bearings on the frame adapted to rotatably engage said pins, and means cooperating with the blade to dispose all four edgesides of the blade to said sharpening element individually and successively. 15
4. A sharpening device for razor blades comprising a frame provided with end members, a carriage arranged for reciprocation in said frame, a blade holder pivotally mounted in said carriage, a plate having an aperture therein and supported by the end members, a pair of bearing projections upstanding from said plate, a sharpening element rotatably supported between said projections to permit rotation of said element in the frame relatively thereto and provided with a pair of recesses, said element, being confined between the side edges of the aperture and having a honing side and a stropping side and adapted to interpose either the honing or the stropping side to the blade edge, means actuated by the manual reciprocation of the carriage to move the cutting edge of the blade toward said sharpening element and means supported by said plate and cooperating with one of said recesses for restricting the free rotation of said element in the frame whereby either the honing or the stropping side of said sharpening element is interposed to the blade edge. 20
5. A sharpening device for razor blades comprising a frame, a carriage arranged for manual reciprocation in said frame, a plate supported in said frame, a pair of bearing projections located on said plate, a sharpening element rotatably mounted on said projections and having a honing side and a stropping side and having its axis of rotation disposed obliquely to the direction of the movement of said carriage, said element being adapted to be reversed in the frame through 180° about said projections to bring either the honing or the stropping side into operative position against the blade edge, and means actuated by the reciprocation of the carriage to dispose the cutting edge of a blade to said sharpening element. 25
6. A sharpening device for razor blades comprising a frame provided with end members, a slidably mounted carriage in said frame, a blade holder pivotally supported in said carriage, a plate rigidly supported on said end members, a pair of bearing projections located on said plate, a sharpening element rotatably supported on said projections with the axis thereof oblique to the direction of the movement of said carriage, said element being adapted to be reversed in the frame through 180° about said projections to interpose either the honing side or the stropping side to the blade edge of the blade carried by the blade holder, and means supported by said plate for restricting the free rotation of said element in the frame during the honing or stropping operation. 30
7. In a razor stropping device provided with a frame, the combination with a reciprocating blade holder, of means for reversing the blade holder at each end of the stroke thereof, a sharpening element, a member provided with a honing surface arranged on one face of the sharpening element, a member provided with a stropping surface on another face of the sharpening element, stationary bearings at the ends of the element for pivotally supporting said sharpening element in the path of the blade, whereby said element may be rotated around relatively 35 to the frame on said bearings and means for locking the element in the position into which it has been rotated in the bearings to arrange either of said surfaces in operative relation to the blade. 40
8. In a sharpening device for razor blades the combination with a frame provided with end members, of a carriage arranged for reciprocation in said frame, a blade holder rotatably mounted in said carriage, a plate having an aperture therein and supported by the end members, a pair of bearing projections upstanding from said plate, a sharpening element rotatably supported between said bearing projections to permit rotation of said element around in the frame on said projections, spring means interposed between said element and said projections for resisting the free rotation of said element. 45
9. A sharpening device for razor blades, comprising a frame provided with end members, a carriage slideably mounted in said frame, a blade holder pivotably supported in said carriage, a plate supported on said end members, a pair of bearing projections arranged on said plate, a sharpening element provided on one side with a honing element and on the opposed side with a stropping element, said sharpening element rotatably supported between said projections with the axis thereof obliquely disposed to the direction of movement of said carriage, said sharp- 50

- 60
- 65
- 70
- 75

ening element being rectangular in cross section and having pyramidically shaped ends, said sharpening element adapted to be reversed in said frame through 180 degrees on said projections to interpose either the honing element or the stropping element to the blade edge of the

blade carried by the blade holder, and means supported by said plate for restricting the free rotation of said element during the honing or stropping operation.

JOHN HOLTZMAN.
